STRETCHING SCREW

Lars Fredriksson, Vaxjo, Sweden, assignor to
K. A. Bergs Smide AB, Gemla, Sweden

Filed Aug. 1, 1975, Ser. No. 601,190

Claims priority, application Sweden Jan. 31, 1975

Term of patent 14 years

Int. Cl. D8—08

U.S. Cl. D8—229

FIG.1

FIG.2

FIG. 1 is a front plan view of a stretching screw showing my new design; and

FIG. 2 is a perspective view of my stretching screw as seen from the left in FIG. 1, the ends of the stretching screw being rotated with respect to the central portion of the stretching screw.

I claim:

The ornamental design for a stretching screw, as shown and described.
